[57] CLAIM

The ornamental design for a tool shank for an abrasive article, as shown and described.

DESCRIPTION

FIG. 1 is a front elevational view of a tool shank for an abrasive article showing my new design, the rear elevational view is a mirror image thereof;

FIG. 2 is a right end elevational view thereof;
FIG. 3 is a top plan view thereof, the bottom plan view is a mirror image thereof; and

FIG. 4 is a left end elevational view thereof.
The rear and bottom view are mirror images of the front and plan views, respectively.

FIG. 1

FIG. 2

FIG. 3

FIG. 4

UNITED STATES PATENT AND TRADEMARK OFFICE
CERTIFICATE OF CORRECTION

PATENT NO. : D318 781

DATED : August 6, 1991

INVENTOR(S) : Nobuo NISHIKI

It is certified that error appears in the above-identified patent and that said Letters Patent is hereby corrected as shown below:

Title page, item (75):

Please insert the inventor's new address

--No. 406, Sanko Dai-Roku Heights,
15-7, Izuo 4-chome, Taisho-ku,
Osaka-shi, Osaka-fu, Japan--.

Signed and Sealed this

Fifteenth Day of June, 1993

Attest:

MICHAEL K. KIRK

Attesting Officer

Acting Commissioner of Patents and Trademarks
